HOIST

Arthur E. Du Bois, Fort Lauderdale, Fla., assignor to
Aluminum Products, Inc., Fort Lauderdale, Fla., a corporation of Florida

Application December 31, 1953, Serial No. 401,573

4 Claims. (Cl. 254—167)

This invention relates to hoists or mechanical winches and more particularly to a hoist for controlled winding and unwinding cable and the like under load pressure.

An object of this invention is to provide a hoist with holding and loading pawls with cam means co-acting therewith in conjunction with reversibly biasing tension means on the loading pawl to controllably wind and unwind cable under load pressure.

Another object of this invention is to provide a drum-type hoist of the class described with releasable cable securing means for refastening new cable or broken cable.

Another object of this invention is to provide a two-step spring controlled cam for actuating the holding pawl of a hoist of the class described in and out of engagement with a ratchet wheel.

A further object of this invention is to provide a hoist of the class described which will be simple and economical in construction and repair, and efficient and durable in use.

The foregoing and other objects and advantages will be more fully understood from reading the following specification, in conjunction with the drawings forming a part thereof, wherein:

Fig. 1 is a side elevational view of a hoist of this invention as positioned for pulling a load over an overhead pulley;

Fig. 2 is a side elevational view of the hoist of Fig. 1 as viewed from the other side thereof;

Fig. 3 is a fragmentary cross-sectional view taken along line 3—3 of Fig. 1, parts shown in elevation for clarity;

Fig. 4 is a cross-sectional view taken along line 4—4 of Fig. 3, parts shown in elevation for clarity;

Fig. 5 is a perspective view of the loading pawl with reverse biasing ears and spring;

Fig. 6 is a view of the device shown in Fig. 1 with the side of the frame removed to show the relationship of the interior working parts;

Fig. 7 is a face elevational view of Fig. 1, with operating handle removed;

Fig. 8 is a perspective view of the holding pawl and operating cam assembly; and

Fig. 9 is a fragmentary and enlarged cross-sectional view of the drum taken along line 9—9 of Fig. 6, showing releasable cable clamping assembly, parts shown in elevation for clarity.

Referring to the drawings, wherein like members are given the same reference numeral, a substantially rectangular frame 1 has an anchoring hook or eye 2 swivelly mounted in one end along the longitudinal axis thereof. The other end of the frame is provided with a boss 3 spaced inwardly from the end member of the frame 1, and aligned apertures 4 and 5 in said boss 3 and end of the frame 1, respectively, along the longitudinal axis of the frame and adapted to receive and guide a cable 6.

The frame 1 supports a shaft 10 positioned transversely therethrough and press-fitted into bushed apertures 11 provided in the sides of said frame 1. Rotatably mounted

2

on the shaft 10 is a ratchet-wheel drum comprising a cylindrical body 12, an annular flange 14 on one end and a ratchet wheel 15 on the other end. A U-shaped member 16, having approximately the same transverse dimension as the frame 1, has the legs thereof rotatably mounted on the shaft 10, one leg intermediate the flange 14 and side of the frame 1, and the other leg externally of the frame 1 on the side adjacent the ratchet wheel 15. Operably fastened to this latter leg of the U-shaped member 16 is an operating lever or arm 17, in a conventional manner such as nut and bolt assembly 18 and aperture 19 receiving the shaft 10 and a feed pawl shaft 20 described hereinafter.

A transverse feed pawl shaft 20 is rotatably supported by the U-shaped member 16. A loading or feeding pawl 21 is rotatably mounted on the shaft 20 in alignment with the ratchet wheel 15 and held in such alignment by guides 22 and 23, on each side of said pawl 21, fastened to the shaft in any conventional manner, such as set screw 24. The guide 23 has an apertured ear 25 adapted to receive one end of an L-shaped toggle spring element 26 having the other end thereof pivotally mounted in an aperture 27 of the central section of the U-shaped member 16. The feeding pawl 21 is provided with a pair of ears 28 and 29, between which the spring element 26 passes. When the shaft 20 is in the position illustrated in Figs. 3, 4, and 5, the spring element 26 is past its center point and presses against ear 28 to urge the feed pawl 21 into engagement with the ratchet wheel 15; whereas, with the shaft 20 rotated back approximately a fourth revolution, the spring 26 is biased in the opposite direction and pressed against ear 29, raising the feed pawl 21 from engagement with the ratchet wheel 15 and to over-ride the wheel 15. To limit the rotation of feed pawl 21 when in over-ride position, a stop projection 30 is provided on the U-shaped member 16 to abut the spring 26 in this direction of bias. To facilitate rotation of the shaft 20, a knob 31 is fastened to the shaft 20 externally of the U-shaped member 16.

A shaft 40 is journaled in the side members of the frame 1, and pivotally supports a holding pawl 41 thereon whereby the holding pawl is aligned with the ratchet wheel 15 for engagement therewith and pivoted out of engagement therewith. Pivotally mounted to the frame 1 intermediate the frame 1 and holding pawl 41 is a cam element 42, having a projection 43 journaled for free rotation in an aperture 44 in the frame 1. The cam element 42 has an aperture or eye 45 in an end thereof adapted to receive a stud projection 46 on the holding pawl 41. A compression spring 47, illustrated as a U-shaped spring, has one end thereof fastened to the cam 42 and the other end thereof fastened to the stud projection 46 of the holding pawl, urging the holding pawl 41 out of engagement with the ratchet wheel 15; but, another spring element 48 of greater strength than spring 47, illustrated as a tension spring, has one end thereof fastened to the cam element 42 and the other end fastened to the frame, in any conventional manner, such as a pin, to oppose the force of spring element 47 and urge the holding pawl 41 into engagement with the ratchet wheel 15 by the eye 45 abutting the stud 46 and pulling the pawl 41 toward the ratchet wheel 15 over the opposed force of the weaker spring 47. The holding pawl 41 has a projection 49 extending beyond the frame 1 to permit manual disengagement of holding pawl 41 and ratchet wheel 15 by rotating the pawl over the action of the spring 48.

The loading pawl 21 has a lateral projection 51 thereon which abuts a lateral projection 52 on the cam 42, when the loading pawl 21 is in over-ride position, to overcome the action of the spring 48 and permit spring 47 to disengage the holding pawl 41 from the ratchet wheel 15 while

camming the loading pawl 21 into engagement with the ratchet wheel, thus permitting a single ratchet-tooth reverse action of the drum at each step.

The drum cylinder 12 has a chord-wise aperture 55 extending therein and communicating with the end of a longitudinally positioned tapped aperture 56. The free end of the cable 6 is received by the chord-wise aperture 55 and clamped therein by a floating member 57 having a concave end 58 fitting around the cable 6 and forcing the cable against the end of tapped aperture 56 by the action of a plug 59 threadedly engaging the tapped section of aperture 56 and forcing the free floating member 57 toward the end of the aperture 56 clamping the cable 6 therebetween.

In operation, with a cable 6 clamped in recess 55 by the sliding member 57 and knob 31 turned to position the loading pawl 21 in over-ride position, by pulling the holding pawl projection 49 toward the drum 12 to release the holding pawl 41 from the ratchet wheel 15, the cable 6 may be freely moved to a load. When the knob 31 is turned to load position as illustrated in Fig. 1, by raising and lowering the operating handle 17, the loading pawl 21 engages the ratchet wheel 15 to wind the cable 6 onto the drum 12, with the holding pawl 41 operating normally to prevent back rotation of the drum or engaging the ratchet wheel 15.

When it is desired to lower a load which has been raised, the loading pawl 21 is placed in over-ride position by turning the knob 31. Rotation of the operating lever 17 permits the loading pawl 21 to over-ride the ratchet wheel 15 until the projection 51 contacts the cam projection 52, overcoming the force spring 48 to permit spring 47 to force holding pawl 41 from engagement with the ratchet wheel 15, which projection 52 cams the loading pawl 21 into engagement with the ratchet wheel 15. When the lever 17 is reversed the holding pawl 41 engages the ratchet wheel 15 in the next tooth, thus lowering the load one ratchet tooth distance. Repeated action lowers the load, a tooth at a time.

The invention has been described in detail, but it is clearly understood that it is not so limited. Many changes and modifications can be made therein without departing from the spirit and scope thereof as defined in the appended claims.

Having thus described the invention, what is claimed as new and desired to secure by grant of United States Letters Patent is:

1. A hoist comprising a frame, a drum having a ratchet wheel rotatable therewith, an operating lever, a rotatably mounted loading pawl operatively connected with said lever and in alignment with said ratchet wheel, a spring biasing said loading pawl, means selectively biasing said spring to bias said loading pawl in or out of

ratchet engagement, a holding pawl pivotally connected to said frame and in alignment with said ratchet wheel, a cam pivotally mounted intermediate said pawls and positioned to contact and cam said loading pawl into ratchet engagement when said loading pawl is biased out of ratchet engagement, spring means connecting said cam and holding pawl and biasing said holding pawl out of ratchet engagement, and cam holding spring means biasing said cam to urge said holding pawl into ratchet engagement against the opposing bias of said other cam spring means.

2. A hoist as described in claim 1 wherein said cam is pivoted against the bias of said cam holding spring upon contact with the loading pawl to position the holding pawl out of ratchet engagement and cam the loading pawl into ratchet engagement against the bias of the loading pawl biasing spring.

3. A hoist as described in claim 1 in which the loading pawl has two projections thereon, a toggle spring intermediate said projections, and means selectively positioning said toggle spring to exert force upon either of said projections to position the ratchet engaging end of said loading pawl in or out of ratchet engagement.

4. A hoist comprising a frame, a drum, a ratchet wheel, loading pawl, holding pawl, and operating lever, resilient means selectively positioning said loading pawl in and out of ratchet wheel engagement, a pivotally mounted cam intermediate said pawls, resilient means connecting said cam and holding pawl normally urging said holding pawl out of ratchet engagement, cam resilient means urging said cam in a direction opposed to and to overcome said other cam resilient means to position said holding pawl in ratchet engagement, and said loading pawl, holding pawl, and cam being so constructed with projections on said cam and said loading pawl and arranged with said pawls and said cam projection in alignment with said ratchet and said cam and loading pawl projection aligned that operating the loading pawl when positioned out of ratchet engagement abuts said cam and is cammed into ratchet engagement while pivoting the cam against the bias of said cam resilient means to permit said cam and holding pawl resilient means to position said holding pawl out of ratchet engagement.
